UNITED STATES PATENT OFFICE.

WILLIAM BUCHOLT, OF JAMAICA, NEW YORK.

CAP FOR SHADE-ROLLERS.

SPECIFICATION forming part of Letters Patent No. 728,441, dated May 19, 1903.

Application filed January 16, 1901. Serial No. 43,459. (No model.)

To all whom it may concern:

Be it known that I, WILLIAM BUCHOLT, a citizen of the United States, residing at Jamaica, in the county of Queens and State of New York, have invented certain new and useful Improvements in Caps for Shade-Rollers; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to end caps for shade-rollers, its object being to provide a cap which may be adjustably connected to the roller and which forms the support for a spring-pressed pin adapted to enter a hole in an inside 20 bracket on the window-casing. Provision is also made to enable the pin to be retracted in order to disengage it from the bracket.

The invention will be fully described hereinafter, reference being had to the accompanying drawings, in which—

25 Figure 1 is a side elevation of an end portion of a shade-roller with my improved cap thereon. Fig. 2 is a longitudinal section. Fig. 3 shows a group of the several parts 30 detached. Fig. 4 is a face and edge view of the bracket preferably used with my invention.

A indicates the shade-roller, and B a cap adapted to fit over the end of the roller. The outer closed end of the cap is centrally perforated, as indicated at b, for the passage of a pin c, said pin being rigidly connected to or forming part of a disk C, which fits loosely in the cap. Another disk D, or it may be a bar, is secured within the cap, and 35 in the space between this disk D and the disk C is a coiled spring E, which abuts against both disks and normally holds the pin c projecting through the opening b.

At the closed end of the cap a series of slots 40 or openings f are cut at intervals around its periphery, and near the open end a series of perforations g are made around its periphery, these latter being for the passage of tacks to secure the cap to the roller. The slots g are 45 to permit the insertion of a knife-blade or

other flat tool between the disk C and the end wall of the cap to press the disk C back against the force of the spring to disengage the pin c from the bracket.

In Fig. 4 I illustrate a preferred form of 55 bracket to be used with my invention. As shown, it consists of a flat metal plate H with a central opening h for the reception of the pin c. It is also provided with holes i for the passage of nails or screws to fasten it to the 60 casing. In use the plate is nailed in position and an awl or other boring - tool inserted through the opening h to make a hole in the casing of sufficient depth to receive the pin c.

It is well known that the inside width of 65 window - casings supposed to be uniform vary sometimes as much as half an inch, and if rollers have been cut to fit the width the casings are supposed to be it becomes necessary on many occasions to either shorten 70 the roller or to block out the brackets, and this consumes time and in the latter case detracts from a neat finish to the shade-fixtures. All this is obviated by the use of my improved cap, for it can be adjusted on the 75 roller to compensate for any such variations, it being necessary, of course, to cut the rollers to a length somewhat less than the supposed uniform width of the casings. In using the cap it is not permanently fastened to the 80 roller until it is adjusted to make the roller fit the casing, and by omitting the last tack at each end of the roller when securing the shade-cloth thereto such end tacks may be used when the parts are adjusted to secure the cap 85 in place on the roller, as well as the corners of the shade-cloth.

When the caps have been adjusted and secured to the roller, the pin at one end of the roller may be inserted into its bracket and 90 the pin at the other end be retracted to engage the face of its bracket, and then if this end is moved over the face of the bracket until the pin is opposite the opening the spring will at once project the pin into such 95 opening. The roller will be securely supported and cannot be accidentally disengaged from the brackets, as is the case sometimes when one or both brackets have open-ended slots for the reception of the pins, and 100

the shade will come in closer proximity to the casing than with brackets now in common use.

Without limiting myself to the precise constructions illustrated, I claim—

1. The combination of a cap adapted to be adjustably fitted over the end of a shade-roller, the end wall of said cap being centrally perforated, and said cap having a series of slots arranged peripherally adjacent said end wall, a movable plate within the cap having a pin to project through said central perforation, and a spring supported within the cap to engage the said plate and normally holding the pin projected, substantially as set forth.

2. The combination with a shade-roller, of a cap slidably fitted upon the end of said roller,

20 said cap having perforations in its periphery near its inner end for the passage of tacks into the roller and having also slots in its periphery near its outer end, and the end wall of said cap being centrally perforated, 25 a movable disk within the cap having a pin to project through said central perforation, and a spring supported within the cap to engage said disk and normally hold it against the end wall of the cap with the said pin projecting through said central perforation, substantially as set forth. 30

In testimony whereof I affix my signature in presence of two witnesses.

WILLIAM BUCHOLT.
